RAILWAY SWITCH TRACK SAFETY DEVICE

Peter Paul Jargick, West Chicago, Ill.

Application April 25, 1939, Serial No. 269,934

1 Claim. (Cl. 246—452)

This invention relates to railway track safety devices adapted for connection to conventional switch connecting rods and to cooperate with switch points for the purpose of preventing disengagement of said points in the event of breakage of the conventional switch rods by which said switch points are moved to and from the main rails.

At present, switch operating mechanism comprises a connecting rod which extends from the manual or automatic switch operating means to a point near one side of the track where it is connected by a bolt to a flat switch rod known as the No. 1 switch head rod. The switch rod extends under the main rail and split rail or switch point, and said rod is connected to the switch point by means of a clip, one arm of which is bolted to the switch point and the other arm of which is bolted to the flat switch rod. Most frequently breakage occurs in the switch rod at the point where the rod is connected to the clip on the switch point which is then intended to be retained closely adjacent a main rail. Without the safety device of my invention, such breakage results in derailment of trains.

The safety device of my invention, installed as hereinafter described, moves with the connecting rod, switch rod and switch point when said parts are being actuated, but if breakage of the switch head rod occurs so that said rod and the switch point connecting clip become disengaged, my safety device retains its engagement with the switch point and holds it firmly against the rail.

35 In the drawings:

Fig. 1 is a plan view of a section of track and switch in which is installed a safety device embodying my invention.

Fig. 2 is a vertical sectional view, on an enlarged scale, in the plane of the line 2—2 of Fig. 1.

Fig. 3 is a vertical sectional view, on the same scale as Fig. 2, taken in the plane of the line 3—3 of Fig. 1.

Fig. 4 is a plan view similar to Fig. 1, showing my safety device in modified form.

Figs. 5 and 6 are vertical sectional views, on an enlarged scale, in the planes of the lines 5—5 and 6—6, respectively, of Fig. 4.

Fig. 7 is a horizontal section taken in the plane of the line 7—7 of Fig. 6.

A conventional railway track and switch construction comprises main rails 10, 10', split rails commonly called switch points 11, 11', ties 12, connecting rod 13, switch rod 14, and clips 15,

15'. The connecting rod 13 extends from switch operating means (not shown) to a point near one side of the track where it is connected to the switch rod 14. In the present embodiment, the connecting rod 13 has an apertured bifurcated end 16 which is connected to the apertured end of the switch rod 14 by a horizontally disposed bolt 17. The switch rod 14 is a flat metal rod, twisted at 18 so that its horizontally disposed portion extends under the rails 10, 10' and switch points 11, 11', and is connected to the switch points by means of the clips 15, 15'.

Each clip 15 (best shown in Figs. 1, 4, 5 and 6) comprises a vertically disposed arm 19, inclined web 20, and two horizontally disposed apertured arms 21, the latter being connected at one side of the clip by a U-shaped portion 22. The vertical arm 19 is bolted to the switch point 11 by bolts 23, with the web 20 bearing on the base of the switch point, and the horizontal arms 20 21 are bolted by bolt 24 and nut 24' to the flat switch rod 14 which extends through the clip between the arms 21. The bolt 24 may extend through any of the registering apertures 21' in said arms 21.

In conventional track installations such as described, the switch rod 14 is called the switch head rod No. 1, and one or more additional switch rods such as the rod 25 may be provided and be connected by clips 26 to the switch points 11 and 11', as shown in Fig. 1. The clips 26 are similar to the clips 15 and 15'.

It is important to safety that the switch points be maintained normally in their intended positions relatively to the rails 10. In an installation such as shown in Fig. 1, for example, breakage of the switch rod 14 most frequently occurs at its point of connection to the clip 15 on the switch point 11 which is intended normally to bear against the rail 10. The safety device of my invention, about to be described, is an attachment designed to retain the switch points 11 in their intended positions in the event breakage of the switch rod 14 results in disengagement between the rod 14 and the clip 15.

Referring now to that embodiment of my invention shown in Figs. 1, 2 and 3, my safety device comprises a separate clip 30, consisting of a vertical arm 31, inclined web portion 32 and base block 33 horizontally bored as indicated at 34. The base block 33 extends downwardly to a horizontal plane sufficiently below the bottom of the rail 10 and switch point 11 to receive in the bore 34 an eye bolt rod 35. The rod 35 is screw threaded at 36 to receive the nut 37 and at its 38

other end terminates in an apertured flat portion 38 whereby it is connected to the connecting rod 13 by the same bolt 17 which connects the connecting rod 13 and switch rod 14. The rod 35 may be bent between its ends as shown in Fig. 1 to accommodate it to the requirements of the particular installation. After the end 38 of the eye bolt rod 35 has been connected to the connecting rod 13, the nut 37 may be tightened and a cotter pin 39 inserted in the rod end.

The clip 30 bears firmly against one side of the switch point 11 and normally holds it against the rail 10, but when the switch is actuated by the movement of the connecting rod 13 and switch rod 14, the safety device parts 30 and 35 move with the switch point 11.

In Figs. 4 to 7, inclusive, is shown a modified form of my safety device. In this installation, the ties 12 happen to be close together and there is not sufficient space to accommodate a separate clip 30 such as heretofore described. In the modified form, I utilize as part of my safety device the clip 15 by which the rod 14 is connected to the rail point 11. The eye bolt rod 35, in this form, is inserted between the arms 21 of the clip 15, adjacent to and parallel with the switch rod 14. A special square nut 40 having lugs 41 is mounted on the end 36 of the rod 35, with the lugs 41 inserted between the arms 21 of the clip 15. A nut 42 is screwed on the end of the rod 35 to hold the nut 40 and rod 35 in place. The opposite end 38 of the eye bolt rod 35 is connected to the connecting rod 13 by the bolt 17 as heretofore described. The rod 35 is bent between its ends to the extent required to permit its connection to the connecting rod 13, as shown in Fig. 4.

Thus the safety devices comprising the clip 30 and rod 35 (Figs. 1, 2 and 3) or the clip 15, nut 40 and rod 35 (Figs. 4 to 7) prevent dis-

placement of the switch point 11 from its normal position adjacent the rail 10 when breakage occurs in the switch rod 14 at its connection to the clip 15. It will be understood that displacement of the switch point 11' is also prevented by the safety devices of my invention because the switch point 11' is connected to the switch point 11 by the switch rod 25, and therefore both switch points 11 and 11' are held in their intended positions by the safety devices shown and described when breakage occurs in the switch rod 14.

Changes may be made in the details of construction without departing from the scope of my invention.

I claim:

The combination with a pair of railway rails, a pair of switch points, a switch rod connected to both switch points and having a vertically flattened end extending beneath one rail and switch point outwardly thereof, a connecting rod and a bolt connecting said end of the switch rod to the connecting rod, of a safety device comprising a clip having a vertical bearing arm, an inclined web portion and a base, said clip bearing against one of the switch points, a safety rod extending transversely beneath the rail and switch point and through the clip base laterally of the switch rod, said safety rod being round in cross section and having a vertically flattened end connected to the flattened end of the connecting rod by the aforementioned bolt which connects the switch rod and connecting rod, means adjustably mounted on the other end of said safety rod and bearing on said clip for retaining the clip in switch point bearing position, and a second switch rod connected to and extending from one switch point to the other laterally of said first mentioned switch rod.

PETER PAUL JARGICK.
